[57] CLAIM

The ornamental design for a rack for off-road utility/recreational vehicle, as shown and described.

DESCRIPTION

FIG. 1 is a top, front and left side perspective view of the rack for off-road utility/recreational vehicle showing our new design;

FIG. 2 is a bottom, front, right side perspective view thereof;

FIG. 3 is a top view thereof;

FIG. 4 is a bottom view thereof;

FIG. 5 is a left side view thereof (the opposite side being a mirror image thereof);

FIG. 6 is a top, front left side perspective view of a second embodiment thereof;

FIG. 7 is a bottom, front, right side perspective view;

FIG. 8 is a top view of FIG. 6;

FIG. 9 is a bottom view of FIG. 6; and,

FIG. 10 is a left side view of FIG. 6 (the opposite side being a mirror image thereof).
